(57) **CLAIM**

The ornamental design for a display screen with graphical user interface or portion thereof, as shown and described.

DESCRIPTION

This application is related to U.S. Design patent application Ser. No. 29/488,692, filed Apr. 22, 2014, and issued as U.S. Pat. No. D780,777, and to U.S. Design patent application Ser. No. 29/488,695, filed Mar. 14, 2017, and issued as U.S. Pat. No. D781,318, the entire disclosures of which are incorporated herein by reference.

FIG. 1 is a front view of a display screen with graphical user interface or portion thereof, according to a first embodiment of our design; and,

FIG. 2 is a front view of a display screen with graphical user interface or portion thereof, according to a second embodiment of our design.

The broken lines illustrate portions of a display screen with a graphical user interface or portion thereof and form no part of the claimed design. The perimeters of the graphical user interface and the underlying display screen or portion thereof are understood to be flush.
